UNITED STATES PATENT OFFICE.

CHAUNCEY W. BROUGHTON, OF CARLTON, ILLINOIS.

MAIL-POUCH-RECEIVING APPARATUS FOR RAILWAY-CARS.

No. 895,421.

Specification of Letters Patent.

Patented Aug. 11, 1908.

Application filed March 25, 1908. Serial No. 423,109.

To all whom it may concern:

Be it known that I, CHAUNCEY W. BROUGHTON, a citizen of the United States, residing at Carlton, in the county of Dekalb and State of Illinois, have invented certain new and useful Improvements in Mail-Pouch-Receiving Apparatus for Railway-Cars, of which the following is a full, clear, and exact specification.

10 This invention relates to devices for receiving a mail pouch on a car from a station while the car is in motion, and it is designed as an improvement upon an apparatus for this purpose shown and described in my 15 United States Letters Patent No. 880,008, granted February 25, 1908.

In this apparatus the magnets 17 in my former patent which receive the pouch from the device at the station and hold it preparatory to conducting it into the car are magnetized at all times, excepting when the door 2 of the car is opened inwardly and the magnets are drawn into the car for depositing the pouch. This condition might be objectionable in some instances owing to the fact that the powerful magnets would be liable to be attracted by adjacent iron or steel structures, such as steel cars, bridges, etc., and thus prematurely move into their outstanding position.

The primary object of my present invention, therefore, is to demagnetize the receiving magnets while in their running position, or in the position in which they stand when not 35 in readiness to receive a mail pouch from the station and deliver the same into the car.

With a view to the attainment of these ends and the accomplishment of other objects which will hereinafter appear, the invention 40 consists of the features of novelty which will now be described with reference to the accompanying drawings, and more particularly pointed out in the claims.

In the said drawings,—Figure 1 is a diagrammatic plan view of an apparatus embodying my improvement, showing the same in the running position, with the circuit through the receiving magnets broken. Fig. 2 is a similar view showing such circuit closed with 50 the magnets in position for holding a pouch preparatory to delivering it into the car. Fig. 3 is a side elevation of the door.

As the present improvement is designed to

be employed in connection with the operating mechanism shown in my former patent, it is 55 deemed only necessary to illustrate in the present drawings those portions of the invention which constitute the improvement, all other parts not herein fully described being the same in construction and operation 60 as in the patent.

1 is the car wall and 2 the car door which is hinged therein on a vertical axis 3 and capable of opening inwardly. In my present improvement, unlike my former invention, 65 the door 2 is formed with a recess 4 on the outside for receiving the magnets 5 when in their running position, so that they will be flush with the side of the car and reduce the possibility of colliding with objects along the 70 right of way. These magnets 5, as in my former invention, are mounted upon arms 6, 7, secured in a hub 8, which is also hinged on the vertical axis or hinge pintle 3, and as shown in Fig. 3, this hub 8 is supported by 75 the door 2, so that the arms 6, 7 will be capable of a limited independent motion on the hinge 3. The arms 6, 7 are also formed with a bend 9, which enables them to project the magnets 5 into the recess 4 of the door. 80 With this construction it will be seen that the hub 8 may be turned sufficiently to cause the arms 6, 7 to stand outwardly at substantially right angles to the side of the car while the door is closed, so as to be in position for 85 receiving the mail pouch from the apparatus at the station, and the arms are pulled into this position by a spring 10 and a cable 11, as described in my former patent, or they may be pulled from this position into the recess of 90 the door, as shown in Fig. 1 by a cable 12 suitably connected therewith, and with one end of the cable 35, which is operated in the manner described in my former patent by automatic means within the car. When the 95 magnets 5 stand in running position, thus enclosed by the recess of the door, their circuit is broken through one of their circuit wires 41, 42 by a bolt 13 provided with an insulated end 14 adapted to strike and open a 100 switch 15 in the circuit wire 41, and to hold the switch open as long as the magnets remain in their running position. It is obvious, however, that should the bolt 13 have this effect when the magnets swing inwardly 105 after receiving a mail pouch, the magnets

will drop the pouch outside the car, and in order to prevent this result from occurring, the bolt 13 is provided with means for causing it to project normally in the path of one of the arms 6, 7, and thus arrest their inward movement. For this purpose, the bolt is provided with a spring 16, arranged to shoot the bolt into the recess 4 of the door, where it will be engaged by the elbow or bend 9 of one of the arms 6, 7 as shown in Fig. 2. The magnets will remain in this position relative to the door while holding the mail pouch suspended until they, together with the door, are moved entirely into the car by the cable 12 and mechanism described in my former patent, as soon as the hand switch 75 in my former patent is closed, whereupon the circuit through the magnets 5 will be automatically broken as the insulations 46 come under the brushes 49, 50 which supply the magnets 5 with current from the live bars 43, 44 to which the cable 35 is attached. The mail pouch being released, the bolt 13 may be withdrawn manually by a handle or knob 17, and the door 2 thereby allowed to swing outwardly into line with the wall of the car and into close relation to the magnets 5, as shown in Fig. 1, where the insulated end 14 of the bolt will hold the switch 15 open, as before described.

As described in my former patent, the magnet 57 is supposed to hold the magnets 5 in their running position, and in the present improvement the intention is that the magnet 57 shall hold the magnets 5 in their position shown in Fig. 1 entirely within the recess 4 of the door, but it is obvious that if the magnet 57 be so adjusted that its armature 58 will reach the limit of its stroke when the elbow 9 comes to rest against the bolt 13, the magnet 57 could not exert further power upon the magnets 5 to pull them into the recess 4 when the bolt 13 is withdrawn. Consequently the cable 35 is provided with a spring 18, which allows the armature 58 to continue to move after the elbow 9 is arrested by the bolt 13, and consequently when the bolt 13 is withdrawn, the power thus stored up in the spring 18 serves to pull the magnets 5 into their running position within the recess 4, as shown in Fig. 1. It is of course obvious that in order for the spring 18 to have this effect, it must be of greater tension than the spring 10, which serves to throw the arms 6, 7 into their outer position at right angles to the side of the car when the armature 58 is released by the magnet 57.

Having thus described my invention, what I claim as new is—

1. In an apparatus for the purpose described, the combination of means upon a railway car for supporting a mail pouch magnetically, said means being movable into a position outstanding from the car and

also a position in close proximity to the car, and means for demagnetizing said magnetic means when in the latter said position.

2. In an apparatus for the purpose described, the combination of an electro-magnet for supporting a mail pouch upon a car, said magnet being movable into an outstanding position away from the car and to a position adjacent to the side of the car, a circuit for supplying said magnet with current, and means for breaking said circuit when the magnet is moved into the latter said position.

3. In an apparatus for the purpose described, the combination of an electro-magnet for supporting a mail pouch upon a car, said magnet being movable into an outstanding position away from the car and also into a position adjacent to the side of the car, a circuit for supplying said magnet with current, a switch for breaking said circuit, means for pressing said switch open when the magnet is in a position close to the car, and means interposed in the line of inward movement of the magnet for preventing the said switch from being opened as the magnet moves inwardly from its outer position.

4. In an apparatus for the purpose described, the combination of an electro-magnet for supporting a mail pouch upon a car, said magnet being movable into an outstanding position away from the car and also into a position adjacent to the car, a circuit for supplying said magnet with current embodying a switch, a bolt pressing normally toward said switch for opening it when the magnet is in its position adjacent to the car, and means for releasing said bolt manually at will to allow said switch to close.

5. In an apparatus for the purpose described, the combination of an electro-magnet for supporting a mail pouch upon a car, said magnet being movable into an outstanding position away from the car, and also into a position adjacent to the car, a circuit for supplying said magnet with current embodying a switch, a bolt standing normally in the line of movement of the magnet for arresting its inward movement, said bolt being also adapted to engage and open said switch when the magnet moves further inward, and means for pulling said magnets inwardly embodying an elastic medium adapted to continue the inward movement of the magnet when said bolt is withdrawn.

6. In an apparatus for the purpose described, the combination of a car door having a recess in its outer side, an electro-magnet hinged on a vertical axis and adapted to swing into said recess, an electric circuit for supplying said magnet with current having

a switch, a spring actuated bolt arranged to press said switch open when the magnet is in said recess, and means for pulling said magnet outwardly away from the car and allowing said switch to close.

In testimony whereof I have signed my name to this specification, in the presence of

two subscribing witnesses, on this 23rd day of March A. D. 1908.

CHAUNCEY W. BROUGHTON.
